William J. Hoffman

By his Attorney

Augustus B. Stoughton

UNITED STATES PATENT OFFICE.

WILLIAM J. HOFFMAN, OF ATLANTIC CITY, NEW JERSEY.

DESIGN FOR A CLOCK-MOUNT.

56,873.

Specification for Design.

Patented Jan. 4, 1921.

Application filed May 26, 1920. Serial No. 384,465. Term of patent 7 years.

To all whom it may concern:

Be it known that I, WILLIAM J. HOFFMAN, a citizen of the United States, residing at Atlantic City, in the county of Atlantic and State of New Jersey, have invented a new, original, and ornamental Design for Clock-Mounts, of which the following is a specification, reference being had to the accompanying drawing, forming part thereof.

The figure is an elevational view of a clock mount showing my new design.

I claim:

The ornamental design for a clock mount, as shown.

WILLIAM J. HOFFMAN.

Witnesses:

VERNON STANTON,
HEPNER F. OLEN HORN.
